[57] CLAIM

The ornamental design for a water closet, as shown and described.

DESCRIPTION

FIG. 1 is a right, top, front perspective view of a water closet embodying my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

The dotted line representations of holes in FIG. 1, 3, and 6, and of mounting structure in FIG. 7, are for the purpose of illustration only, and form no part of the claimed design.
